DESIGN FOR A TRADE-MARK.

GEORGE W. WESTBROOK, OF NEW YORK.

Design No. 2,513, dated November 27, 1866.

SPECIFICATION.

TO ALL WHOM IT MAY CONCERN:

Be it known that I, GEORGE W. WESTBROOK, of the city, county, and State of New York, have originated and designed a new Device as a Trade-Mark, of which the following is a full, clear, and exact description, reference being had to the accompanying drawings making part of this specification.

The design is an oriental scene, with tropical trees, vines, shrubs, and flowers. To the left, above the centre, is a bold, rocky cliff, from which bursts a fountain of water which falls into a natural basin at its foot; from thence flows a stream or rivulet meandering to the southeast corner of the picture. At the fountain stand two human figures, one on either side of the stream, male and female, both in a state of nudity, the male in the act of offering a drink to the female from a shell. Towards the right of the picture is a grass or rush hammock, suspended over the stream from two trees, in which is a sleeping child. At the top of the picture are the words, "Westbrook's Sparkling Saratoga Water Powders."

Claim.

What I claim as my invention, and desire to secure by Letters Patent, is—
This design for a trade-mark, as shown and described.

G. W. WESTBROOK.
